UNITED STATES PATENT OFFICE

2,127,093

SPRING SEAT CONSTRUCTION

Albert W. Steffens, Pittsburg, Kans.

Application November 16, 1935, Serial No. 50,231

1 Claim. (Cl. 155—179)

This invention relates to furniture constructions and more particularly to an improved spring construction for the seats of furniture, motor vehicles or the like.

5 An object of this invention is to provide in a seat construction of this character a means for suspending springs within a frame so that various portions of the suspended spring structure may move one relative to another, thus permitting the 10 main supporting spring structure to conform to the configuration of the body on the seat.

Another object of this invention is to provide in a spring construction of this character means to prevent twisting of the spring supporting bars 15 so that the main springs will not become twisted.

The above and various other objects and advantages of this invention will in part be described in, and in part be understood from the 20 following detail description of the present preferred embodiment, the same being illustrated in the accompanying drawing wherein:

Figure 1 is a top plan view of a spring seat structure constructed according to an embodiment of this invention.

25 Figure 2 is a sectional view taken on the line 2—2 of Figure 1, showing also a back with the seat structure.

Figure 3 is an enlarged fragmentary sectional view taken on the line 3—3 of Figure 2.

30 Referring to the drawing wherein like symbols designate corresponding parts throughout the several views, the numeral 10 designates generally a frame construction including side bars 13 and front and rear bars 11 and 12 respectively.

35 This frame structure may be constructed out of any suitable material, such as wood or metal, and may be of any suitable configuration depending only upon the character of the article of furniture with which the seat construction is associated.

A plurality of coil springs 14, 15, and 16 are disposed within the frame 10 and the tops of these springs are adapted to engage beneath a conventional covering means, generally designated as 17. The coil springs are supported for individual and independent movement by means

45 of straps 18, 19 and 20, respectively. The strap 18 is disposed at the front of the frame and has a reverted inner end portion 21 provided with a pair of holes through which the forward ends of a pair of coil springs 22 are adapted to engage. These coil springs 22 are disposed in spaced apart relation and the opposite ends of the coil springs 22 engage in holes provided in the reverted forward end portion 23 of the intermediate sup-

porting bar 19. The rear end of the intermediate bar 19 is reverted, as at 24, and the forward ends of rear coil springs 25 engage in spaced apart openings provided in the rear end of the intermediate bar or strap 19. The rear strap or bar 20 has a reverted forward end portion 26 in which the rear ends of the coil springs 25 engage. While I have shown a single intermediate bar 19 between the front and rear bars or straps 18 and 20 respectively, it will be understood that as many intermediate straps 19 may be used as is considered necessary, depending only upon the length of the side rails 13 and the particular type of seat construction with which the seat and spring structure is to be used.

In order to provide a means whereby the front and rear straps or bars 18 and 20 may be rockably connected to the frame 10, I have provided a looped end portion 27 formed by bending the strap 18 in the form of a loop and then spot-welding, as at 28, or otherwise securing the reverted portion of the strap. A hinge bar 29 is adapted to loosely engage within the eye or opening provided by the reverted portion 27 and the opposite ends of the pintle or hinge bar 29 are forwardly offset, as at 30, so that the barrel or loop 27 will be permitted to have free rocking movement with respect to the frame construction. The offset end portions 30 of the pintle 29 are secured as by fastening devices 31 in the form of bolts or the like to the front frame bar 11. The rear strap 20 is hingedly secured to the rear frame bar 12 in the same manner as the front strap 18.

The lower ends of the main coil springs 14, 15 and 16 are secured in any suitable manner to the straps 18, 19 and 20 respectively. A plurality of coil spring suspending means are provided, as shown in Figure 1 of the drawing, with each set of coil springs being disposed in spaced apart relation and permitted to have independent movement one relative to another and as many series of coil springs with the suspending means therefor may be used as are considered necessary to properly maintain the top or cushion structure 17 in a smooth condition.

In the use of this spring structure, the bars 18 and 20 are hingedly secured to opposed frame bars of the frame 10 and, in the present instance, are secured to the front and rear frame bars 11 and 12 respectively. As many bars 18, 19 and 20, with associated coil springs 22 and 25, may be used as are considered necessary, depending on the size of the seat or frame and then the covering structure 17 is secured over the coil springs 55

14, 15 and 16. Due to the independent suspension of the coil springs 14, 15 and 16, it will be obvious that when a weight has been placed on the covering 17 these springs 14, 15 and 16 will 5 move in a vertical direction so that they will not have a tendency to become twisted and this resistance to twisting of the coil springs is resisted by the pairs of springs 22 and 25 which suspend the intermediate straps or bars 19 between the 10 end straps or bars 18 and 20. Due to the independent suspension of the coil springs 14, 15 and 16, the seat structure will more readily conform to the body of the person seated thereon and in this manner the seat structure will be more comfortable and will also be more durable because of the fact that the coil springs are mounted in a manner whereby the movement thereof will be a vertical movement rather than an angular movement, particularly the intermediate springs.

15 20 I claim:—

A spring structure comprising a substantially rectangular frame, a plurality of parallel spaced apart members disposed within the frame, each member comprising a pair of metallic outer strap members, an intermediate metallic strap member, 5 each of said strap members having reverted opposite ends with the outer ends of said outer strap members having loops integral therewith, pairs of spaced apart springs connecting the adjacent ends of said outer strap members with said intermediate strap member and engaging through the reverted ends of said strap members, a pintle extending through each looped end, offset ends carried by each pintle, means securing each offset end to said frame, and a vertically disposed 10 coil spring carried by each strap, said coil springs having the lower ends thereof fixedly secured to a strap.

ALBERT W. STEFFENS. 20
